MUFFLER FOR EXHAUST GAS SYSTEM

Floyd E. Deremer, Livonia, Mich., assignor to Oldberg
Manufacturing Company, Grand Haven, Mich., a cor-
poration of Michigan

Application June 17, 1954, Serial No. 31,057

Term of patent 14 years

(Cl. D14—6)

Fig. 1

Fig. 2

Fig. 3

In the drawing, Figure 1 is an elevational view of a muffler for exhaust gas system showing my new design;

Figure 2 is an enlarged fragmentary elevational view of the muffler shown in Figure 1, and

Figure 3 is a transverse view showing my muffler design.

The ends of the muffler of my design are of conventional construction.

I claim:

The ornamental design for a muffler for exhaust gas system, substantially as shown and described
